US00D921029S

(12) **United States Design Patent** (10) Patent No.: **US D921,029 S**
(45) Date of Patent: **** Jun. 1, 2021**

(54) **ELECTRONIC DEVICE WITH GRAPHICAL USER INTERFACE**

(71) Applicant: **Apple Inc.**, Cupertino, CA (US)

(72) Inventors: **Eduardo Ahumada Apodaca**, Thousand Oaks, CA (US); **Vincenzo O. Giuliani**, Thousand Oaks, CA (US); **Harry Payne**, London (GB)

(73) Assignee: **Apple Inc.**, Cupertino, CA (US)

(**) Term: **15 Years**

(21) Appl. No.: **29/705,044**

(22) Filed: **Sep. 9, 2019**

(51) LOC (13) Cl. **14-04**

(52) U.S. Cl.

USPC **D14/487**

(58) **Field of Classification Search**

USPC **D14/485-495**

CPC **G06F 3/048-04897**

(57) **CLAIM**

The ornamental design for an electronic device with graphical user interface, as shown and described.

DESCRIPTION

FIG. 1 is a front view of a display screen or portion thereof with graphical user interface showing the claimed design; FIG. 2 is a second embodiment thereof; FIG. 3 is a third embodiment thereof; and,

FIG. 4 is a front view of an electronic device having a display screen with the graphical user interface of FIG. 1 applied to the display screen. The graphical user interface designs of FIGS. 2 and 3 may be similarly applied thereto. The outer broken lines in the figures show a display screen or portion thereof, or an electronic device having a display screen, and form no part of the claimed design. The other broken lines in the figures show portions of the graphical user interface that form no part of the claimed design.

1 Claim, 2 Drawing Sheets
